A. S. SPIEGEL,

SHINGLE,

APPLICATION FILED MAY 25, 1917.

1,251,704.

Patented Jan. 1, 1918

Inventor:

Alexander S. Spiegel,
Newark, N. J.
Atty.

UNITED STATES PATENT OFFICE.

ALEXANDER S. SPIEGEL, OF CHICAGO, ILLINOIS.

SHINGLE.

1,251,704.

Specification of Letters Patent.

Patented Jan. 1, 1918.

Application filed May 25, 1917. Serial No. 171,047.

To all whom it may concern:

Be it known that I, ALEXANDER S. SPIEGEL, a citizen of the United States, and resident of Chicago, Illinois, have invented a certain new and useful Improvement in Shingles, of which the following is a specification.

The present invention is an improvement in a shingle of the self-spacing type, the article being, however, novel in itself and different from anything heretofore known in that it gives a self-spacing effect on both sides.

In the accompanying drawing,

The figure is a face view of my improved shingle.

My invention constitutes a self spacing shingle having each of its side walls notched and with the notches arranged centrally, the parts of the shingle being of different widths but having their edges extending in parallel lines except where the notch connects the two widths and by reason of the fact that the notch is central the shingles may be cut

without waste from a blank, as the intermediate sections will be in reverse positions 25 where they are cut from a single strip of the exact length of the complete shingle. The shingle may be cut out of a strip or out of a sheet as may be desired.

What I claim is:

A self spacing shingle having each of its side walls notched to form a space, the notches being centrally arranged of the shingle whereby a series of shingles may be cut from a sheet of material in reverse position so as to prevent all waste, the shingle having a narrow and a wide part with the edges extending in parallel lines, substantially as described. 35

In testimony whereof, I affix my signature.

ALEXANDER S. SPIEGEL.
